UNITED STATES PATENT OFFICE.

JERRY L. SHEA, OF SHREVEPORT, LOUISIANA.

OIL-WELL APPARATUS.

Application filed December 20, 1921. Serial No. 523,638.

To all whom it may concern:

Be it known that I, JERRY L. SHEA, a citizen of the United States of America, and a resident of Shreveport, parish of Caddo, and State of Louisiana, have invented certain new and useful Improvements in Oil-Well Apparatus, of which the following is a specification, reference being had to the accompanying drawings, forming a part 10 thereof.

This invention relates to apparatus for oil wells and more particularly to equipment which may be employed for cleaning out such wells whereby their productivity may 15 be increased.

Oil wells may be said to be of two general classes, first, those which extend through ground material of substantially similar character throughout the depth of the well, 20 and in this class it is customary for the diameter of the bore of the well to be the same throughout the well; and second, wells which are drilled into ground of unlike characteristics through its depth and in 25 which a stratum of sand for example, usually the oil bearing stratum, is encountered. In drilling wells of the second class, it is usual to drill through one of these strata a bore having the ordinary diameter and when 30 the second stratum is encountered to change the diameter of the bore so as to provide a hole of restricted diameter therethrough. The diameters of such wells, when completed, are in fact determined by the diameter 35 of the casing inserted in the well as the drilling operation proceeds, and in sinking wells of this class, it is customary to make a transition from the casing of relatively large diameter to a casing of relative small 40 diameter at a point somewhat above the sand stratum.

In the operation of oil wells, the portion of the well which is in the oil producing zone becomes clogged up by the accumulation 45 of foreign matter, such as mud, water and the like, and thus the flow of oil is interfered with. As the accumulation of foreign matter continues, the interference gradually increases until finally it may be 50 that the flow of oil is not sufficient to render the operation of the well worth while. When this point has been reached in wells of the first named class, it has been the practice to clean out these accumulations by lowering 55 into the well special equipment for cleaning out purposes. The operation in cleaning out

such a well is commonly known as swabbing and the apparatus for the purpose is known as a "swab". Accordingly, in the present specification and claims the term "swab" 60 will be employed for designating cleaning equipment for oil wells.

Heretofore, oil wells of the second class have not been swabbed out as described, there being no apparatus available for the 65 purpose, and it is the object of the present invention, broadly stated, to provide a swab for use in wells having two or more diameters of bore and extending into strata of 70 varying character, whereby the productivity of such wells may be materially increased and the productive life of a well substantially lengthened.

A feature of the invention resides in the provision of a packing means of improved 75 construction by which the equipment adapted to enter the portion of the well having the restricted diameter may be operatively connected with that portion which only enters the part of the well having the relatively large diameter.

Another feature relates to the provision of a check valve of improved construction whereby the flushing out fluid may be conducted between the portions of the well of 80 unlike diameter in only a predetermined direction.

Another feature relates to the provision of a pair of separable sealing members which are adapted to cooperate with each other to 85 form an effective seal for removing substantially all of the foreign material when the swab is withdrawn from the well.

Another feature relates to the provision of a check valve at the bottom of the swabbing-out apparatus of improved construction, and this valve forms one of the improved 90 elements of the present invention.

Among the novel features of this valve is the provision of a valve opening which 100 permits the inrushing of the large quantities of flushing-out fluid required to thoroughly clean out the well, with a minimum of resistance and interference to its passage; the provision of an inclined seat of 105 novel and improved design whereby the valve is quickly and efficiently closed to prevent the flow of liquid in undesired directions; the provision of a movable valve member of improved construction, having its center of gravity so adjusted that the valve is 110 automatically and reliably closed; and the

provision of an adjustable element having the double function of displacing the center of gravity of a movable member and of limiting movements thereof.

5 Other objects will appear from the following description of the invention taken in connection with the drawings, in which

10 Fig. 1 is a side elevation of the swab of the present invention in place within the well, with a portion of the well casing cut away,

15 Fig. 2 is a longitudinal section of the portion of the swabbing apparatus adapted to cooperate with the part of the well of relatively large diameter,

20 Fig. 3 is a longitudinal section of the portion of the swabbing apparatus adapted to cooperate with the part of the well having restricted diameter,

25 Fig. 4 is a horizontal cross-section taken on the line 4—4 of Fig. 2,

Fig. 5 is a horizontal cross-section taken on the line 5—5 of Fig. 2,

30 Fig. 6 is a horizontal cross-section taken on the line 6—6 of Fig. 2,

Fig. 7 is a horizontal cross-section taken on the line 7—7 of Fig. 3,

35 Fig. 8 is an enlarged view of the lower portion of the swabbing apparatus of Fig. 3, and

Fig. 9 is a horizontal cross-section taken on the line 9—9 of Fig. 8.

40 Like reference characters denote like parts in the several figures of the drawings.

45 Referring to the drawings and more particularly to Fig. 1, there is shown an oil well having a casing 10 extending through the stratum 11. At a point 12, a relatively short distance above the upper level of the sand or other paying stratum 13, the casing 10 terminates and from approximately this point to the bottom of the well there extends a second casing 14 of a diameter relatively smaller than the diameter of the casing 10.

50 the casings 10 and 14 are secured in position in the well in any desired manner. The upper end of the lower casing 14 may protrude somewhat into the casing 10. The upper portion of the casing 10 terminates above the level of the ground in a usual casing head 15, having a centrally positioned orifice for the passage of the well pumping and cleaning apparatus and having a conducting passage 16 connected to suitable pumping apparatus, as for example, a vacuum line for withdrawing fluid from the well.

55 A packing gland 17 of conventional design is provided for passing a supporting element such as a wire line or cable rope 18 through the casing head. A portion 19 of the wire line extends to a usual hoisting apparatus, such as hoisting drum, in a convenient position nearby, the wire rope being passed over a suitable crown block at the top of the usual derrick (not shown). For the purpose of

operating the apparatus there may be provided at the mouth of the well a walking beam 20 of conventional design. After the swabbing apparatus has been inserted into the well, as will be subsequently set forth, the reciprocating end of the walking beam may be operatively connected with the well portion of the wire rope 18 by means of a usual temper screw 21. The arrangement is such that oscillatory motion of the walking beam 20 will be transmitted to the temper screw 21, a flexible joint being provided between the walking beam 20 and temper screw to compensate for the arcuate movement of the end of the walking beam.

55 The rope 18 is affixed at its well end to a rope socket 30 whose outer periphery at its upper end is provided with a plurality of grooves such as 31 for the attachment of a fishing tool when the socket 30 is "lost" in the well. The lower end of the rope socket 30 is screw-threaded to one of a series of sinker rods such as 32, secured together in longitudinal relation. The lowermost one of the rods 32 is attached to a reducing nipple 33 which in turn is screw-threaded to a swabbing pipe 34 having a diameter somewhat greater than the rods 32. The pipe 34 is provided with a number of perforations such as 35 extending radially through its walls for a purpose which will be subsequently set forth. Secured outwardly to the lower portion of the swabbing pipe 34 is an elongated packing 36, the outer wall of the pipe 34 being provided with grooves in order

60 that the packing may be securely attached thereto. Surrounding the pipe 34 at an intermediate portion thereof below the lowermost perforation 35 and adjacent the upper face of the packing 36 is an annular valve member 37 whose exposed surface is curved to form a valve seal. For compressing the packing 36 to a desired degree there is provided a collar 38 and a pair of nuts 39, one of which serves as an adjusting nut and the other of which serves as a lock nut. It will be seen that when the nuts 39 are adjusted to compress the packing 36, the packing is forced against the member 37. Thus the member 37 serves the double purpose of providing a valve seal and of retaining the packing 36 in position. The normal adjustment is preferably such that the packing 36 will pass through the casing 14 but that pressure between the member 37 and the packing 36 will distend the packing 36 against the casing of the well. The adjustment may be changed during the life of the apparatus to compensate for wear of the packing.

65 A tubular valve chamber 40 is screw-threaded to the lower portion of the swabbing pipe 34. Screw-threaded in the chamber 40 is a plug member 41 having an eccentric orifice 42 extending longitudinally

therethrough. The plug member 41 is thus in the form of a shell and its upper end is cut off diagonally to form an inclined seat for a movable valve cover 43. The valve cover 43 comprises an arm 44 pivotally mounted upon the shell 41 having secured thereto a sealing member 45. A nut 46 preferably of relatively massive construction is mounted near the free end of the arm 44 and serves the double purpose of limiting the extent of movement of the valve member 43 by coming in contact with the wall of the chamber 40 and of rendering the center of gravity of the cover 43 at all times displaced from the vertical plane of its pivot, so that the valve is normally held in closed position by force of gravity.

The swabbing apparatus for the part of the well of relatively large diameter comprises a plurality of sections such as shown in Fig. 2, secured to each other in longitudinal relation, surrounding rope 18 and slidably mounted within the casing 10. The uppermost one of these sections includes a packing box 50 having on its upper periphery a plurality of grooves such as 51 for engagement with the usual fishing tool.

The packing box 50 comprises a hollow reducing nipple 52 having an interior recess 53 of relatively large diameter and a longitudinally extending passageway 54 of restricted diameter, thus forming an annular shoulder 55. A packing gland 56 is provided in the upper portion of the recess 53 and is held in place by a packing ring 57 pressed against the packing by a compression spring 58.

The nipple 52 is screw-threaded to the upper one of a plurality of sections 60 secured to one another in longitudinal relation in any suitable manner, as for example, by means of couplings such as 61 of conventional construction. The pipe 60 may be made of suitable drill pipe having an outside diameter such as will readily fit within the casing 10. The lowermost section 60 is secured to a pipe section 62 forming part of a lift check valve. The lower portion of pipe 62 is screw-threaded to a pipe 63 forming a packing support to the lower end of which there is in turn secured a valve seal member 64.

The lowermost one of the drill pipe sections 60 has in its interior passage a disc 70 having a single perforation suitably mounted in position by means of a pair of split expansion rings such as 71. The cable 18 passes through the perforation of the disc 70 and thus the escape of fluid from the lower portion of the well at undesired periods is substantially prevented. The pipe section 62 has a portion 73 of restricted diameter relative to portion 74. The change in outside diameter is gradual there being provided an inclined convex

shoulder 76. The change in inside diameter, however, is made by a stepped shoulder 77 in a plane transverse to the longitudinal axis of the pipe 62.

For providing fluid conducting passages from the interior of the lift check valve to the exterior thereof, a number of spaced channels 80 extend diagonally through the shoulder formed by the surfaces 76, 77 these passages being preferably positioned along radial lines as shown in Fig. 4 and each disposed at an angle to the surface of the incline 76. Mounted upon the surface 76 is a pair of packing rings 81, 82. Surrounding and slidably mounted upon the restricted portion of the pipe 62 is a lift member 83 having its lower annular surface cut to correspond with the slope of the surface 76, and arranged to be seated upon the packing rings 81, 82. The arrangement is such that the lift check valve is normally closed by the action of gravity, forcing the member 83 downwardly into contact with the packing rings 81, 82 and preventing the passage of fluid downwardly. When the fluid presses upwardly, however, with a pressure exceeding a predetermined amount, the member 83 is lifted and displaced from its seat thereby permitting the escape of fluid through the channels 80 in an upward and outward direction.

Mounted directly upon the exterior of the intermediate portion of the pipe 63 is a packing 90 formed of a suitable material, such as rubber or the like. This is held in place by a collar 91 pressed against the lower extremity of the pipe section 62 and by a second collar 92, which in turn may be adjustably positioned by means of a pair of nuts 93. It will be seen that the farther up the nuts 93 are placed, the greater is the compression against the rubber packing 90. The normal adjustment is preferably such that the packing 90 will pass through the casing 10, although it may be varied to compensate for wear.

The valve seal member 64 comprises an annular flange arranged to be screw-threaded to the lower extremity of the section 63 and having its interior rounded out to correspond with the shape of the convex surface of the member 37. The arrangement of the parts is such that when the member 64 contacts with the member 37 an effectual seal is made for preventing the escape of any fluid which may be retained in the chamber formed by the pipe sections 63, 62, and so much of 60 as is below the disc 70.

In the operation of an oil well, when it becomes necessary to swab out the well, the upper portion comprising the portion formed by the upper casing 10 is first swabbed out either with a mechanism similar to the swab herein shown or with any other suitable swabbing mechanism of prior construction.

The swabbing out of the upper portion of the well forms no part of the present invention and detailed description thereof is, therefore, omitted. This part of the operation, however, will be made obvious from the following description relating particularly to cleaning out the lowermost portion of the well.

In the operation of a system embodying the present invention for cleaning out the lowermost portion, i. e., the portion of restricted diameter, the portion of the swabbing mechanism shown in Fig. 2 is maintained above the portion shown in Fig. 3, so as to form the assembly illustrated in Fig. 1. The entire swabbing mechanism is then lowered into the well and a connection, such as shown in Fig. 1, is made to the walking beam. The walking beam is then operated. On each of the downward strokes of the walking beam the valve shell 40 is forced downwardly into the mud or other foreign material within the well and the mud or other foreign material is trapped on each upward stroke by the closure of the valve member 43.

It will be seen that the diameter of the collar 92 is relatively larger than the diameter of the casing 14, so that when lowered into the well a face of the collar 92 contacts with the upper edge of the inner casing 14. Thus when the swab has been lowered so that the portion shown in Fig. 3 has entered the restricted casing 14, substantially the entire weight of the portion of Fig. 2 is supported upon the collar 91. The packing 90 is thus jammed in between the collar 92, which is in fixed position by virtue of its contact with the casing 14 and is subjected to a compression due to the weight mentioned. It is therefore distended outwardly against the larger casing 10 and forms an effective seal for the casing 10. Escape of fluid upwardly between the packing 90 and the interior wall of the casing 10 is thus effectually prevented.

When a sufficient load of fluid has been introduced above the packing member 36, the usual mechanism may be made active for drawing up the wire rope 18. The fluid trapped by the previous reciprocatory action of the walking beam is now drawn upwardly through the section 63 and not being able to pass the disk 70 is forced through the passages 80 of the lift check valve 83. The fluid passes into the space between the outer surface of the sections 60 and the inner wall of the casing 10, being maintained therein by the lift check valve. A number of loads may be introduced into this space by reciprocatory action of the lower portion of the swabbing apparatus shown in Fig. 3. After a number of loads have thus been drawn, the entire swab is drawn out of the well and all of the liquid trapped, both in the lower portion and in the upper portion of the swabbing apparatus is raised to the surface.

After the fluid in the well has been cleaned out in this manner the lower swab is operated at various points in the paying sand strata. The oil passes through the perforations in the lower portion of the casing 14 through the normal operation of the well, and it is therefore, of importance to thoroughly clean out these perforations. Accordingly, the swabbing mechanism is employed in a manner similar to that already described at various points in the paying strata and the reciprocatory action caused by the walking beam forces fluid through the check valve into the pipe 34 and out through the perforations 35. The fluid is prevented from flowing directly back by means of the packing 36 and upon the upward stroke of the walking beam, the fluid will be forced out through the perforations 35 and into the sand and subsequently returned to the check valve 43. Obstructions in the perforations in the casing are removed by this churning operation and in case any of these obstructions are of such nature as to collect in the bottom of the casing, they may be subsequently removed in any well known manner, as for example, by means of a sand pump.

The swabbing mechanism of my invention may be employed in connection with wells having casings of more than two diameters, it being obvious that a desired number of sections of the general type shown in Fig. 2 are provided. In case such increased number of sections are employed, the upper portions of each of the intermediate sections are formed in accordance with the upper portion of the section of Fig. 3, the dimensions of the parts being such that the various sections will cooperate.

It will be seen that I have provided a swabbing mechanism for efficiently cleaning out wells having casings of unlike diameters, whereby the lowermost portions of the well may be thoroughly swabbed out, thus the operation of the wells of this type may be continued for extended periods, their productive life being subsequently increased by the use of the present invention.

Illustrative apparatus has been described for the purpose of showing a way in which this invention may be practiced, but the inventive thought upon which this application is based is broader than the illustrative embodiment thereof, and I therefore intend no limitation other than those imposed by the appended claims.

What is claimed is:

1. Apparatus for swabbing a well casing having sections of varying diameters comprising a string of tubular members secured to each other in longitudinal relation and slidably mounted within the section of the casing of larger diameter, one of the lower members being closed against the upward flow of the liquid therethrough and another

of said members being formed with a portion of increased diameter so as to form an inclined annular shoulder constituting a valve seat having a plurality of radial ports 5 extending therethrough, an annular valve slidably mounted on the restricted portion of said tubular member and adapted to close said ports, packing disposed on the lowermost member of said string of tubing adapt- 10 ed to form a liquid seal with the wall of the casing, and means for raising liquid encountered in the sections of the well casing of smaller diameter and for forcing the same upwardly through a portion of the string of 15 tubular members and through the outlet ports into the well casing above the packing member.

2. Apparatus for swabbing a well casing having sections of varying diameters comprising means for cleaning the walls of the lower casing and for raising any liquid encountered in the lower casing to the upper casing, a tubular member in the upper cas- 20

ing adapted to receive the liquid from the lower casing and formed with a portion 25 thereof of increased diameter, the upper end of the enlarged portion being formed with an inclined annular shoulder constituting a valve seat through which extend a plurality of radial ports, an annular valve member 30 slidably mounted on the restricted portion of the tubular member and having its lower surface formed to correspond with the slope of the valve seat and adapted to form a liquid seal therewith, means disposed above 35 said radial ports for preventing the upward flow of liquid through the tubular member, means directly beneath said tubular member for cleaning the walls of the larger casing and forming a substantially liquid tight seal 40 therewith, and means for raising said tubular member in the well casing to expel the liquid discharged through the radial ports.

In witness whereof I have hereunto set my hand this 12th day of December 1921.

JERRY L. SHEA,
